JOURNAL BOX LUBRICATING DEVICE

Alfred A. Hamer, Alexandria, Va.

Application July 17, 1952, Serial No. 299,370

4 Claims. (Cl. 308—83)

This invention relates to journal box lubrication, the primary object of the invention being to improve generally the construction as embodied in my Patent No. 2,571,235.

An important object of the invention is to provide a body or block of absorbent yieldable material so constructed that it provides an enclosed oil reservoir within the base of the journal box, which sealed reservoir prevents loss of oil through the front and rear openings in the journal box and the entrance of water and foreign matter to the oil supply, the body or block of yieldable material being provided with openings through which a wick is threaded, portions of the wick lying within the oil reservoir, while other portions of the wick are held in contact with the journal contained within the journal box, supplying lubricating material to the journal by capillary attraction.

A further important object of the invention is to so construct the body or block of yieldable material that a plurality of openings are provided therethrough, the openings establishing communication between the reservoir and the portion of the wick contacting with the journal.

Still another object of the invention is to construct the block of yieldable material in such a way that a pumping action is produced through the openings of the block of yieldable material, with the downward compressions of the body or block of yieldable material by the journal as induced by impacts and low rail joints incident to the rolling stock moving over the rails of a railway track.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing,

Figure 1 is a vertical sectional view through a journal box equipped with a lubricating means constructed in accordance with the invention, the journal being shown as contained within the journal box.

Fig. 2 is a sectional view taken on line 2—2 of Fig. 1.

Fig. 3 is a sectional view taken on line 3—3 of Fig. 2.

Referring to the drawing in detail, a journal box is indicated generally by the reference character 5 in which the journal 6 of conventional construction, operates.

The reference character 7 indicates horizontally disposed ribs which are an integral part of standard journal boxes, such ribs providing stops against which the yieldable body 8 constructed preferably of synthetic sponge rubber material known as "neoprene" contacts the ribs 7 holding the yieldable body 8 within the journal box, both against vertical movement and sidewise rolling by rotation of the journal. However, due to compression

2

fit of the yieldable body portion within the journal box, the ribs 7 are not necessary to prevent displacement of the lubricating device.

Reinforcing members 9 constructed of semi-rigid rubber, metal or the like material, are molded or otherwise secured along the lower edges of the yieldable body 8, bracing the lower edges of the body 8.

As shown, the upper surface of the body is curved to conform to the curvature of the journal 6 contained within the journal box, and the upper curved surface of the yieldable body provides a support for the wick 10, which is held in contact with the journal 6, as clearly shown by Fig. 2 of the drawing, the wick passing through openings formed in the yieldable body 8, the edges of the wick lying within the reservoir 11 formed between the yieldable body 8 and bottom of the journal box.

Depending from the yieldable body 8 and disposed longitudinally along the longitudinal axis of the body, 20 is the rib 12 which is formed with a plurality of openings 13 into which oil from the reservoir 11 passes upwardly to the wick.

It will further be seen that due to the construction, 25 the lubricant contained within the reservoir of the device is maintained clean and guarded against foreign matter and moisture entering the reservoir to impair efficiency of the lubricant.

As clearly shown by Fig. 2 of the drawing, the inner surfaces of the openings 13 at points adjacent to the 30 edge of the rib 12, are flared to direct oil upwardly through the openings, as the central portion of the yieldable body 8 is compressed downwardly by the journal due to impacts and low rail joints incident to the railway rolling stock of which the journal and journal box 35 form a part, moving over the rails of a railway track.

Thus it will be seen that with the downwardly compression movement of the yieldable body 8, a pumping action is set up to cause the oil to be directed against the wick 10 which in in turn delivers the oil directly to the bottom of the journal 6, to be carried upwardly in contact with the journal bearing 14 riding on the journal.

It will also be seen that the natural resiliency of the lubricating device will maintain a constant contact over the journal surface, at proper and controlled pressure for desirable lubrication and resistance to wear.

As clearly shown by Fig. 1 of the drawing, the block or yieldable body 8 extends forwardly to a point adjacent to the front lower wall of the journal box, where it is provided with an opening in which the metal tube 15 is disposed, there being provided a cap 16 closing the metal tube. This tube 15 constitutes means whereby lubricating oil may be supplied to the reservoir 11 to replenish the supply of oil therein, and through which the oil level may also be determined.

In use, it is obvious that with each downward movement of the journal 6, a pumping action will be set up causing quantities of oil to be directed upwardly through the openings of the yieldable body 8, saturating the wick 10 in addition to the quantity of oil supplied to the wick through capillary attraction and by the exudation or squeezing forth of a certain amount of retained oil in the absorbent material of the yieldable body portion as the latter flexes.

Having thus described the invention, what is claimed is:

1. The combination with a journal box and journal operating therein, of a journal lubricating device comprising a yieldable body constructed of porous absorbent material fitted within the journal box providing an oil chamber between said yieldable body and bottom of said journal box, said yieldable porous body having lateral openings extending vertically therethrough, a wick fitted within

said openings and overlying the upper surface of the yieldable body and with which said journal operating within the journal box contacts, the ends of said wick extending through said lateral openings and lying in the oil chamber through which oil passes by capillary attraction to the upper surface of said yieldable body lubricating said journal, a rib extending downwardly from the bottom of said porous body and disposed within said oil chamber, said rib having a line of vertical openings extending through the center thereof establishing communication between said chamber and the upper surface of said porous body, through which oil is pumped onto said wick as said yieldable body flexes within the journal box.

2. The combination with a journal box and journal operating therein, of a journal lubricating device comprising a yieldable body fitted within the journal box in contact with the side and end walls thereof, said yieldable body having curved upper and lower surfaces, and having openings disposed vertically therethrough, the lower surface of said yieldable body being spaced from the bottom of the journal box providing an oil chamber with the journal box, a wick resting on said curved upper surface of said yieldable body and with which the journal operating within the journal box contacts, the ends of said wick extending through said vertical openings and being submerged in oil in said oil chamber, a rib formed along the longitudinal center of said yieldable body, said rib having a line of openings formed therein communicating between said oil chamber and the upper surface of said yieldable body through which lubricating material is pumped to the upper surface of said yieldable body and wick upon vertical or lateral movement of the yieldable body within the box, as induced by journal contact.

3. The combination with a journal box and journal operating therein, of a journal lubricating device comprising a yieldable body fitted within the journal box, the lower surface of said yieldable body being spaced from the bottom of said journal box providing an oil chamber between said yieldable body and bottom of said journal box, and a wick resting on the upper curved sur-

face of said yieldable body and with which the journal operating within the journal box contacts, said wick extending through said yieldable body portion, the ends thereof being submerged in the oil in said oil chamber through which oil passes by capillary attraction to the upper surface of said wick, and said body having openings to said wick through which oil is pumped to said wick as said yieldable body flexes within the journal box, as induced by journal contact.

4. The combination with a journal box and journal operating therein, of a journal lubricating device comprising a yieldable body fitted within the journal box with the side edges thereof resting against the wall of said journal box, the upper surface of said yieldable body being curved, the lower surface of said yieldable body being spaced from the bottom of said journal box providing an oil chamber between said yieldable body and bottom of said journal box, a wick resting on the upper curved surface of said yieldable body with which said journal contacts, said wick extending through openings formed in said yieldable body portion and held against movement by frictional contact with the walls of the openings, the ends of said wick being submerged in the oil in said oil chamber and through which oil passes by capillary attraction to the upper surface of said yieldable body, and said yieldable body having a plurality of spaced vertical openings arranged along the longitudinal axis of said yieldable body, portions of the yieldable body at the edges of said openings extending into said chamber submerged in the oil of said chamber, through which oil is pumped from said oil chamber to said wick overlying said openings, with the vertical flexing of said yieldable body.
